GAME BOARD OR THE LIKE

Norman T. Duesbury, Toronto, Ontario, Canada

Application March 29, 1957, Serial No. 45,506

Term of patent 3½ years

(Cl. D34—5)

I claim:

The ornamental design for a game board or the like, substantially as shown.
